UNITED STATES PATENT OFFICE.

PAUL JONES, OF WHITMAN, MASSACHUSETTS, ASSIGNOR TO COMMONWEALTH SHOE AND LEATHER COMPANY, OF WHITMAN, MASSACHUSETTS, A CORPORATION OF MASSACHUSETTS.

DESIGN FOR A SHOE OR SIMILAR ARTICLE.

Application filed October 11, 1924. Serial No. 11,031. Term of patent 3½ years.

To all whom it may concern:

Be it known that I, PAUL JONES, a citizen of the United States of America, residing at Whitman, in the county of Plymouth and Commonwealth of Massachusetts, have invented a new, original, and ornamental Design for a Shoe or Similar Article, of which the following is a specification, reference being had to the accompanying drawing, forming a part thereof.

In said drawing,—

The figure is a perspective view of a shoe showing my new design.

I claim:

The ornamental design for a shoe or similar article, substantially as shown.

Signed by me at Whitman, in the county of Plymouth and Commonwealth of Massachusetts, this ninth day of October, 1924.

PAUL JONES.
